UNITED STATES PATENT OFFICE.

DAVID McNAIR, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 14,269, dated September 11, 1883.
Application filed August 6, 1883. Term of patent 3½ years.

To all whom it may concern:

Be it known that I, DAVID MCNAIR, of Boston, in the county of Suffolk and State of Massachusetts, have invented a new and original 5 Design for Carpets, of which the following is a specification.

The nature of my design is fully shown in the accompanying photographic illustration.

The design is composed of the bouquets or 10 masses of flowers and foliage of different sizes, and having diverging sprays and leaves around their margins, and the mottled groundwork, as shown.

I claim—

The design for a carpet, substantially as 15 shown and described.

In testimony whereof I have signed my name to this specification, in the presence of two subscribing witnesses, this 17th day of July, 1883.

DAVID McNAIR.
